UNITED STATES PATENT OFFICE.

ERNEST F. McCARTHY, OF DARIEN, CONNECTICUT.

DESIGN FOR A COMBINATION LAMP AND SMOKER'S SET.

Application filed October 27, 1926. Serial No. 19,491. Term of patent 14 years.

To all whom it may concern:

Be it known that I, ERNEST F. McCARTHY, a citizen of the United States, residing at Darien, in the county of Fairfield and State of Connecticut, have invented a new, original, and ornamental Design for a Combination Lamp and Smoker's Set, of which the following is a specification, reference being had to the accompanying drawing, forming part thereof, wherein the figure is a perspective view of a combination lamp and smoker's set showing my new design.

I claim—

The ornamental design for a combination lamp and smoker's set as shown.

ERNEST F. McCARTHY.
